US0D1031080S

(12) **United States Design Patent** (10) Patent No.: **US D1,031,080 S**
(45) Date of Patent: ** Jun. 11, 2024

(54) **ANTI-NOISE CASE FOR MEDICAL DEVICES**

(71) Applicant: **TEIJIN PHARMA LIMITED**, Tokyo (JP)

(72) Inventor: **Nozomi Miya**, Tokyo (JP)

(**) Term: **15 Years**

(21) Appl. No.: **35/517,848**

(22) Filed: **Dec. 27, 2022**

(80) **Hague Agreement Data**

Int. Filing Date: **Dec. 27, 2022**

Int. Reg. No.: **DM/227575**

Int. Reg. Date: **Dec. 27, 2022**

Int. Reg. Pub. Date: **Jul. 21, 2023**

(30) **Foreign Application Priority Data**

Jun. 30, 2022 (JP) ..... 2022-014118 D

(51) **LOC (14) Cl.** **24-99**

(52) **U.S. Cl.**

USPC **D24/232; D3/203.1**

(57) **CLAIM**

The ornamental design for an anti-noise case for medical devices, as shown and described.

DESCRIPTION

1. Anti-noise case for medical devices

1.1 : Perspective

1.2 : Front

1.3 : Left

1.4 : Right

1.5 : Top

1.6 : Bottom

1.7 : Back

The broken lines shown in the drawings are for illustrative purposes only and form no part of the claimed design.
